UNITED STATES PATENT OFFICE.

CHARLES S. MESSINGER, OF BROOKLYN, NEW YORK.

DESIGN FOR A CLOTH FABRIC.

SPECIFICATION forming part of Design No. 16,318, dated October 6, 1885.

Application filed June 9, 1885. Serial No. 168,183. Term of patent 3½ years.

To all whom it may concern:

Be it known that I, CHARLES S. MESSINGER, a resident of Brooklyn, in the county of Kings and State of New York, have invented and produced, by my own industry, genius, efforts, and expense, a new and original Design for Cloth Fabric, of which the following is a full description, in connection with the accompanying drawing, which represents a face view of my new design for cloth fabric.

This invention relates to a design for a cloth fabric; and it consists of the new ornamentation of the face of a cloth fabric.

In the accompanying drawing the cloth fabric is shown at A. On its face appear diagonal stripes *a a*, that are composed of parallel lines, as shown; and between these diagonal stripes the face of the fabric has other diagonal stripes, which present the effect

known as "tricot." This is represented at *b b*—that is to say, there are series of substantially parallel dashes, in rows, between the said diagonal stripes *a*, the rows of dashes being at an acute angle to the said diagonal stripes; but said dashes are at right angles to the lines that compose the stripes *a*, as shown.

I claim—

The design for the ornamentation of cloth, the same consisting of the diagonal stripes *a* and intervening diagonal stripes, in which are the tricot dashes *b* at right angles to the lines composing said stripes *a*, substantially as shown.

CHARLES S. MESSINGER.
